UNITED STATES PATENT OFFICE.

WILLIAM GENTRY SHELTON, OF ST. LOUIS, MISSOURI.

METHOD OF AND MEANS FOR WAVING HAIR.

Application filed December 31, 1926. Serial No 158,333.

This invention relates to a method of and means for waving hair, and more particularly to a system in which coils of hair are subjected to hot moisture. One of the objects 5 is to effectively transmit heat from an electric heating element to the hair. To illustrate this feature I have shown a tube of absorbent paper which surrounds and contacts directly with the coiled hair and a tube of 10 metal foil surrounding and contacting with the absorbent paper, the outer face of the metal foil being exposed to transmit heat from a surrounding heating element to the absorbent paper. The absorbent material is 15 saturated with a liquid and this wet material is in direct contact with both the hair and the metal foil, the latter being exposed to the heating element, so the heat is very effectively transmitted through the metal. In 20 addition to serving as an efficient heat-transmitting medium, the metal tube itself prevents undue escape of vapor, so it is not necessary to use an additional tube of paper, or the like, which would interfere with the 25 transmission of heat.

Another object is to indicate the temperature in the device. In the preferred form of the invention, the metal foil is provided with a sight opening through which a portion of 30 the absorbent tube is exposed for inspection, and the upper portion of this tube is exposed above the metal foil. The absorbent tube may be impregnated with coloring material which changes color when exposed to the 35 heat and moisture of the curling operation, so the exposed portions of this tube will give a very satisfactory indication of the temperature at the hair.

Another object is to produce a simple and 40 inexpensive method of using a tube of this kind without incurring the risk of dropping hot water onto the scalp. With this object in view, the tube of absorbent material is dipped into a liquid without allowing the 45 upper portion of the tube to contact with the liquid, and the tube is then inverted and placed around the coil of hair so as to locate the relatively dry end portion of the tube at the lower portion of the coiled hair. A sufficient quantity of moisture will be absorbed 50 into the relatively dry lower portion of the tube, but the danger of dropping hot water onto the scalp is entirely eliminated.

With the foregoing and other objects in 55 view, the invention comprises the novel method, construction, combination and ar-

rangement of parts hereinafter more specifically described and illustrated in the accompanying drawings, wherein is shown the preferred embodiment of the invention. 60 However, it is to be understood that the invention comprehends changes, variations and modifications which come within the scope of the claims hereunto appended.

Fig. 1 is a side elevation illustrating the 65 device as it appears when in service, the electric heating element being shown by dotted lines.

Fig. 2 is an enlarged vertical section taken on the line 2—2 in Fig. 1, the thicknesses of 70 the paper and metal foil being exaggerated to more clearly show the same.

Fig. 3 is an enlarged transverse section on the line 3—3 in Fig. 1, with the hair and curling rod omitted, the thicknesses of the 75 paper and metal foil being exaggerated.

Fig. 4 is a vertical section of a vessel, showing how the double tube is dipped into a liquid.

To illustrate the invention I have shown 80 a curling rod 1 (Fig. 2) around which the hair is coiled as shown at 2, the hair being attached to the rod by means of a string 3 in the usual manner.

The means for transmitting heat and moisture to the coiled hair comprises an inner tube 4 preferably made of several thicknesses of absorbent paper, such as blotting paper, and an outer tube 5 made of metal foil, such as aluminum foil, wrapped around the 90 paper. This simple and inexpensive double tube can be made as a unit, and when in service, the absorbent tube 4 lies between and contacts with the hair and the metal tube 5. The outer face of the metal tube is exposed 95 to the heat radiated from an ordinary electric heating element (Fig. 1), which surrounds the tubes and rests upon a felt pad 7 at the bottom of the device.

A sight opening 8 is formed in the metal tube 5 to expose a portion of the absorbent tube 4, and this tube 4 is preferably impregnated with coloring material which changes in color when exposed to the heat and moisture of the waving operation. In 100 actual practice I have used a pink coloring material which gradually changes to a dark brown shade during the heating operation, and the operator can obtain a reasonably accurate indication of the temperature by observing the color at the sight opening 8.

The metal tube 5 is preferably shorter than 110

the absorbent tube 4 so that the ends of the absorbent material will be exposed beyond the metal tube.

After this double tube has been arranged around a coil of hair, the lower portion of said tube is crimped as shown at 9 in Fig. 1 and Fig. 2, but the upper portion is preferably left open so that the upper end of the absorbent tube 4 will be exposed to the hot

10 moisture. The color of this upper end will be changed during the heating operation, thereby giving a further indication of the temperature of the hot moisture.

10 designates a vessel containing water or 15 other liquid to be absorbed by the tube 4. The double tube 4, 5 is dipped into the liquid as shown in Fig. 4 without allowing the upper portion of the absorbent tube to contact with the liquid. The double tube is then inverted and placed around the coil of hair to locate the relatively dry end portion of the tube 4 at the lower portion of the hair. The moisture will gradually pass into this lower portion by absorption and gravity, but 25 there will be no danger of water dropping onto the scalp for the water tending to drop by gravity will be quickly absorbed by the relatively dry lower portion of the absorbent material.

30 I claim:

1. In a hair waving device, a unitary double tube comprising a tube of absorbent paper having its inner face exposed to contact directly with the hair, and a tube of metal foil surrounding and contacting with said absorbent paper, the outer face of said metal foil being exposed for the transmission of heat to the absorbent paper.

2. In a hair waving device, a new article of manufacture consisting of a double tube comprising a tube of absorbent paper adapted to surround and contact with a coil of hair, and a metallic foil surrounding and contacting with said paper tube, the outer face of said metallic foil being exposed for the transmission of heat to said paper tube, and said metallic foil being united with said paper tube and provided with a sight opening through which a portion of said paper tube is exposed for inspection.

3. In a hair waving device, absorbent material adapted to surround and contact with a coil of hair, said absorbent material being impregnated with coloring material adapted to change in color when exposed to the heat of the waving operation, and a metallic tube surrounding and contacting with the colored absorbent material, the outer face of said metallic tube being exposed to provide for the transmission of heat to said absorbent ma-

terial, and said metallic tube being provided with a sight opening through which a portion of said colored absorbent material is exposed for inspection.

4. In a hair waving device, a tube of absorbent paper adapted to surround and contact with a coil of hair, said paper tube being impregnated with coloring material adapted to change in color when heated, and a metallic tube surrounding and contacting with 65 said paper tube, the outer face of said metallic tube being exposed to provide for the transmission of heat to said paper tube, the upper margin of said paper tube being exposed for inspection above said metallic tube, 70 and said metallic tube being provided with a sight opening through which a lower portion of said paper tube is exposed for inspection.

5. The method of waving hair which comprises forming a coil of the hair to be waved, dipping a tube of absorbent material into a liquid without allowing the upper end portion of the tube to contact with the liquid, then inverting the tube and placing it around the coil of hair so as to locate its relatively dry end portion at the lower portion of the coil, and then heating said absorbent material.

6. The method of waving hair which comprises forming a coil of the hair to be waved, forming a tube of metal foil around a tube of absorbent paper and leaving the end portions of the paper tube exposed for inspection beyond the ends of the metal tube, dipping the tubes into a liquid without allowing the upper end portion of the paper tube to contact with 90 the liquid, then inverting the tubes and placing them around the coil of hair so as to locate the relatively dry end portion of the paper tube at the lower portion of the coiled hair.

7. The method of waving hair which comprises forming a coil of the hair to be waved, forming a tube of metal foil around a tube of absorbent paper and leaving the end portions of the paper tube exposed for inspection 105 beyond the ends of the metal tube, dipping the tubes into a liquid without allowing the upper end portion of the paper tube to contact with the liquid, then inverting the tubes and placing them around the coil of hair so 110 as to locate the relatively dry end portion of the paper tube at the lower portion of the coiled hair, crimping the lower portion of the metal tube and leaving the upper portion open for the escape of moisture, and heating 115 said tubes.

In testimony that I claim the foregoing I hereunto affix my signature.

WILLIAM GENTRY SHELTON.
